UNITED STATES PATENT OFFICE.

WILLIAM H. REDNOUR, OF DUGGER, INDIANA.

RAILROAD GRASS-LINE AND DITCH CUTTER.

Application filed November 27, 1926. Serial No. 151,180.

This invention relates to an attachment for a railroad motor car such as used by section gangs when working along the railroad "right of way" and has for its object 5 to provide a device which may be readily attached or removed from the motor car and which functions as a ditch cutter and also as a grass line cutter.

Another object of the invention resides in 10 the provision of means for causing the automatic detachment of the apparatus from the motor car should the cutter encounter any obstruction which would otherwise cause a derailment of the car and other damage. 15 Other objects and advantages of the invention will be apparent from the following description when taken in connection with the accompanying drawings in which:

Figure 1 is a plan view of the improved 20 device attached to the side of a railway motor car, the latter being partly broken away.

Figure 2 is a detail view of the cutter disc and the arm on which it is rotatably mounted.

25 Figure 3 is a section through the disc.

Figure 4 is a detail view of a portion of the safety mechanism; and

Figure 5 is a section on the line 5—5 of 30 Figure 1.

Referring to the drawing in greater detail, the numeral 1 indicates a railway motor car of ordinary construction such as used by section hands in repairing the road-bed, etc., and which is provided with a forwardly extending beam 2 at each side.

Mounted above and below this beam are two plates 3 and 4 secured by means of bolts 5 and 6 and a set screw 7, and extending a substantial distance laterally beyond 40 the side of the car. Also extending through the plates 3 and 4 are bolts 8 and 9 between which is located the bent end of a plate portion 10 to which is pivotally connected at 11 a telescoping arm 12 comprising a tube 13 and rod 14 slidably received therein. To the outer end of the rod 14 is secured a cutter disc 15 on which is mounted a circular knife 16. This cutter disc is keyed to a rotatable bearing 17 and is secured to the 45 end of the rod 14 by means of washer 18 and cotter pin 19 as more clearly shown in Figure 3 of the drawing.

In order to provide for adjustability of 50 the cutter with respect to the railroad motor car the tube 13 is provided with a plurality of pins 20 and the rod 14 is provided with

openings or apertures 21 throughout a considerable portion of its length to receive these pins 20 and thereby permit of optional adjustment of the cutter.

In order to secure the proper cutting angle for the disc cutter 15, a bend 22 is provided in the outer end of the rod 14, as will be observed from Figure 1 of the drawing. This bend is made in a horizontal plane and positions the disc in the manner shown. This position of the disc provides for cutting the outer edge of a ditch. If now it is desired to cut the inner edge of the ditch while the car is traveling in the same direction, the pins 20 should be withdrawn and the rod 14 rotated about its axis through 180° and the pins then reinserted into the apertures 21. This rotation of the rod 14 will bring the bend into its opposite position in the horizontal plane as shown in Figure 2 and thereby properly positions the disc for cutting the inner edge of the ditch. It being understood, of course, that after the rod is turned through 180° the disc 15 is 75 removed, by removing cotter pin 19 and washer 18, and inverted, as shown in Figure 2.

It is necessary, of course, to provide some 80 means for connecting the outer end of the rod 12 with the forward portion of the car, and for this purpose I have provided a chain 23, although obviously other types of connecting means may be used if found desirable. This chain is connected to the rod 90 14 as indicated by ring 24, and the forward end of the chain 23 is adjustably connected to a tension-release device 25 which is anchored to the forward part of the car as indicated by numeral 26. This tension-release device comprises two plates 30 and 31 which are mounted on a pin 32 so as to permit movement toward and from each other, and a spring device 33 serves to bias these two plates toward each other. The ends 100 of the plates remote from the pin 32 are provided with cup-shaped members 34 and located between these cup-shaped members is a ball 35 integrally formed on a plate 36. It will be obvious therefore that if an excessive tension is placed upon the chain 23 105 the spring 33 will permit the cups 34 to be spread apart by the ball 35.

The purpose of the tension-release device 110 25 just described as well as the pins 8 and 9 for mounting the rod 13, is to prevent derailment or other damage to the railroad

motor car in the event that the cutter should encounter an obstruction during the operation thereof. Obviously if the cutter should engage an obstruction on the "right of way" 5 which would put upon the connection 23 a tension greater than that for which the tension-release mechanism is adjusted, the parts 34 and 35 will become separated thereby allowing the arm 12 to swing rearwardly and it is apparent that as soon as 10 the arm swings rearwardly a few degrees the plate 10 will draw away from its position between the pins 8 and 9 and allow the car to proceed without derailment or other 15 damage.

The operation of the several parts of the mechanism has been fully described in connection with the description of the mechanism itself and a repetition of the complete 20 operation of the parts is believed to be unnecessary. Briefly stated, however, the present construction provides a rotatably mounted cutter suitable for cutting the grass line along the right of way of a railroad or to 25 cut the ditch line along the side of the railroad bed and to permit this to be done while the car is traveling in a single direction; this being accomplished by means of the bend 22 which will properly position the 30 cutter through the rotation of the rod 14 of the telescoping arm through 180°. Should the cutter meet with an obstruction or other impediment to its forward movement it will automatically become detached from the car 35 thereby preventing derailment or the like.

From the foregoing description taken in connection with the accompanying drawings it will be apparent that I have devised a 40 relatively simple and inexpensive railroad grass line and ditch cutter which may be readily attached to the railway motor cars now in extensive use, which provides for mechanically cutting grass and ditch lines through the movement of the car itself, and 45 which also provides against derailment or other damage to the car in the event that the cutter meets with an obstruction such as a cross tie or the like, and which further provides by means of simple adjustment for 50 cutting both sides of a ditch while the car may continue to move in the same direction.

In accordance with the patent statutes I have described what I now believe to be the best embodiment of the invention, but I do 55 not wish to be understood thereby as limiting myself or the scope of the invention, as many changes and modifications may be made without departing from the spirit of the invention; all such I aim to include in 60 the scope of the appended claims.

What I claim as new and desire to secure by Letters Patent is:

1. The combination with a railway car, 65 of a grass line cutter, an arm on which said cutter is rotatably mounted, and means for

connecting the arm with the car whereby the arm will become disengaged from the car if the former hits an obstruction.

2. The combination with a railway car, 70 of a grass line cutter, an arm on which said cutter is mounted, means for connecting the arm with the car, and an overload release connection between the outer end of the arm and the forward part of the car.

3. The combination with a railway car, 75 of a grass line cutter, an arm on which said cutter is mounted, means for connecting the arm to the car so as to permit its release if the cutter hits an obstruction, a connection between the outer end of said arm and the forward part of said car, said connection provided with a releasable joint adapted to be disconnected when subjected to a predetermined strain.

4. The combination with a railway car, 80 of a grass line cutter, an arm on which said cutter is mounted, means for releasably supporting the inner end of said arm on the car, a connection between the outer end of said arm and the forward part of the car, and a tension-release mechanism in said connection.

5. The combination with a railway car, 85 of a grass line cutter, an arm on which said cutter is mounted, and means for detachably connecting the inner end of said arm with the car, said means including a plurality of pins between which the inner end of said arm is situated.

6. The combination with a railway car, 90 of a grass line cutter, an arm on which said cutter is mounted, and means for detachably connecting the inner end of said arm with the car, said means including a plurality of pins between which the inner end of said arm is situated, a curved portion of the arm extending beyond one of the pins.

7. The combination with a railway car, 95 of a grass line cutter, an arm on which said cutter is mounted, means for detachably connecting the inner end of said arm with the car, said means including a plurality of pins between which the inner end of said arm is situated, and a tension-release connection 100 between the outer end of said arm and the forward part of the car.

8. The combination with a railway car, 105 of a grass line cutter, an arm on which said cutter is mounted, means for releasably connecting said arm with the car, a connection between the outer end of said arm and the forward part of said car, said connection including a ball and a pair of spring-pressed cups between which said ball is received.

9. The combination with a railway car, 115 of a grass cutter, an arm connected to the car and on which said grass cutter is mounted, the end of the arm to which the cutter is attached having a slight bend in a horizon- 120

tal plane, whereby the cutter may be properly positioned to cut either side of a ditch while moving in the same direction by turning the arm about its axis through 180°.

5 10. The combination with a railway car, a laterally extending arm on said car and comprising two telescoping sections, a grass

cutter rotatably mounted on the outer end of said arm, the section of the arm carrying the cutter being provided with a slight bend 10 in a horizontal plane, and means for locking said section in either of two positions with the bend in a horizontal plane.

W. H. REDNOUR.
